UNITED STATES PATENT OFFICE.

JUNIAUS A. LOVE, OF ROANOKE, VIRGINIA.

TROLLEY-GUARD.

1,125,353.

Specification of Letters Patent.

Patented Jan. 19, 1915.

Application filed September 8, 1914. Serial No. 860,729.

To all whom it may concern:

Be it known that I, JUNIAUS A. LOVE, a citizen of the United States, residing at Roanoke, in the county of Roanoke and 5 State of Virginia, have invented a new and useful Trolley-Guard, of which the following is a specification.

This invention relates to trolley guards designed to prevent the wheel of a trolley 10 from jumping off of the wire, one of the objects of the invention being to provide a guard so mounted, that when the trolley cord is pulled for the purpose of lowering the trolley, the guard will first be shifted 15 relatively to the trolley pole so as to become disengaged from the wire after which the wheel is free to move downwardly with the cord and away from the wire.

A further object is to provide a guard 20 which, while allowing the wheel to move downwardly from the wire when the guard is moved to a predetermined position under the action of the trolley cord, will operate, while in its normal position to positively 25 prevent displacement of the wheel relative to the wire.

A further object is to provide a guard which permits the ready placing of the wheel upon the wire.

30 With the foregoing and other objects in view which will appear as the description proceeds, the invention resides in the combination and arrangement of parts and in the details of construction hereinafter described and claimed, it being understood 35 that changes in the precise embodiment of the invention herein disclosed can be made within the scope of what is claimed without departing from the spirit of the invention.

In the accompanying drawings the preferred form of the invention has been shown.

In said drawings: Figure 1 is a side elevation of the trolley wheel, the guard and the pole being shown in section on the line 45 A—B of Fig. 2. Fig. 2 is a plan view of the trolley wheel, fork and guard. Fig. 3 is a section on the line C—D of Fig. 1. Fig. 50 4 is a section on the line E—F of Fig. 1. Fig. 5 is a view showing diagrammatically the different positions to which each of the guard fingers may be moved.

Referring to the figures by characters of 55 reference 1 designates the harp of the trolley-

ley supporting a bearing pin 2 on which is mounted the trolley wheel 3. A sufficient distance is provided between each finger of the harp and the adjacent side of the wheel 3 to receive a segmental plate 4 which is 60 mounted to swing freely on the bearing pin 2 and has a depending arm 5 from which projects a laterally extending finger 6 extending across the lower portion of the grooved periphery of the wheel 3. The 65 fingers 6 on the two arms 5 lap as shown and are secured together by means of rivets 7 or in any other suitable manner. These fingers are so located that they are capable of swinging freely within the harp. Additional fingers 8 extend inwardly from the plates 4 at the rear edges thereof and adjacent the upper portion of the wheel, these fingers 8lapping and having registering 70 openings therein, through which extends a 75 ring 10 engaged by the trolley cord 11. A pin 12 connects the segmental plate close to the fingers 8 and has a sleeve 13 loosely mounted thereon and constituting a roller.

A spiral spring 14 extends around the 80 bearing pin 2 between each of the plates 4 at the adjacent side of the harp 1 and one end of each spring is secured to the harp while the other end is secured to the adjacent side plate 4. Thus it will be seen that 85 the said plates 4 are held normally with their connected fingers 6 within the lower portion of the harp 1 and with the fingers 8 directly in rear of the wheel 3.

Mounted in each plate 4 at a point normally a short distance back of the vertical plane in which the axis of the wheel 3 is located, is a bushing 15 of insulating material, this bushing being provided with a slot 16. A slot shank 17 is slidably mounted in each slot 16 and is provided, at its outer end, with a cylindrical portion 18 and the head 19. A coiled spring 20 is mounted on the cylindrical portion 18 and bears at one end against the head 19 and at its 100 other end against the bushing 15.

A wear plate 21 is mounted upon the inner end of each bushing 15 and the shank 17 extends loosely through it. The inner end of the shank 17 projects into and is pivotally connected to the forked inner end 22 of a retaining pin 23. The greater portion of this retaining pin is cylindrical, the free end of the pin being tapered as shown at 24, while the inner or pivoted end is preferably 110

substantially rectangular in outline so that a flat bearing face 26 is normally pressed against the plate 21 by the spring 20. The two retaining fingers 23 are so proportioned that, when they are in their normal positions, they extend close together although out of contact.

When the wheel 3 is in engagement with a trolley wire, indicated by dotted lines at 10 W in Fig. 1, the retaining pins 23 extend over but out of contact with the wire, while the sleeve or roller 13 extends under but out of contact with the wire. Furthermore, the pivots at the inner ends of the retaining pins 23 extend upwardly along lines radiating from the bearing pin 2, so that, should the trolley wheel move downwardly and carry with it the plates 4 and the parts connected thereto, the lower portions of the pins 23 would strike the top of the wire W without, however, yielding upwardly, this being due to the fact that the pivots at the inner ends of the pins 23 are extended substantially in the direction of such downward movement of the wheel 3. Should the car to which the trolley is attached be moving forward during this downward movement of the trolley wheel there would of course be more or less drag upon the pins 20 by the trolley wire but inasmuch as the trolley wheel would immediately spring upwardly after leaving the wire, the pins would not be in contact with the wire W a sufficient length of time to enable the wire to pull the pins out of retaining position. When, however, it is desired to remove the trolley from the wire, the cord 11 is pulled downwardly. As this cord is connected to the guard, the plates 4 will be swung rearwardly and downwardly about the pin 2 so that the back portions of the pins 23 will be swung rearwardly and downwardly onto the wire which thus causes the pins to swing upwardly about their pivots and to slip 45 downwardly past the wire. After the plates 4 have reached the limits of their downward movement relative to the harp 1, further pulling on the cord 11 will result in the lowering of the harp and the disengagement of 50 the wheel 3 from the wire.

When it is desired to replace the wheel upon the wire W, the foregoing operation is reversed, the upper portions of the pins 23 striking against the lower portion of the 55 wire and swinging downwardly about their pivots until they have slipped upwardly past the wire whereupon they will automatically assume positions across the top of the wire. As soon as the pins are thus positioned, and the plates 4 are brought to their normal positions, the wheel 3 will come into engagement with the wire. The sleeve or roller 13 limits the forward swinging movement of the plates 4 relative to the harp, by coming into contact with the wire.

The springs 20 are always under compression and, as they constantly press against the head 19, they hold the flat faces 26 of the pins 23 pressed firmly against the plates 21. Consequently, when the pins 23 are shifted out of their normal positions in alinement with the shank 17, the corner portions of the forks 22 will push against the plates 21 and further compress the springs 20, so that, as soon as the pins 23 have been relieved of pressure, the said springs 20 will restore the pins to their normal or intermediate positions, as shown by full lines in Fig. 5. The position of each pin when moving into and out of engagement with a wire has been indicated at a and b, respectively in Fig. 5.

What is claimed is:—

1. In a trolley, a harp, a trolley wheel, a structure mounted to swing freely within the harp, yielding means for holding said structure normally in a predetermined position relative to the harp, yieldingly mounted guard elements carried by the structure and adapted to extend over a wire, and means for rotating said structure relative to the harp to move said elements against and past the wire and to lower the harp and wheel.

2. In a trolley the combination with a harp, and a trolley wheel, a structure mounted to swing freely within the harp and extending upwardly past the sides of the wheel, yielding means for holding said structure in a predetermined position relative to the harp, a guard element yieldingly and pivotally connected to the structure and adapted to overhang a wire engaged by the wheel, said element constituting means for engaging the wire during the momentary downward movement of the harp to prevent displacement of the wheel from the wire, and means connected to the structure for successively rotating said structure relative to the harp, thereby to position the element upon the wire to shift upwardly when pressed against the wire and to lower the wheel and harp.

3. In a trolley the combination with a harp, and a trolley wheel, of a structure mounted to swing within the harp, yielding means for holding said structure normally in a predetermined position relative to the harp, yieldingly held retaining members carried by the structure and normally extending over the wheel, said members being adapted to overhang a wire engaged by the wheel, the pivots of said members being normally so positioned as to prevent upward swinging movement of the members when brought against the wire during the momentary downward jumping of the wheel from the wire, and means connected to said structure for swinging the structure relative to the harp, thereby to shift the positions

of the retaining members relative to the wire and drag them downwardly past the wire, said means constituting means for subsequently lowering the harp and wheel from 5 the wire.

4. In a trolley, the combination with a harp and a trolley wheel, of a structure mounted to swing within the harp and at opposite sides of the wheel, yielding means 10 for holding said structure normally in a predetermined position relative to the harp, a pivoted guard member carried by each side portion of the structure and normally extending over the wheel and adapted to 15 extend over the wire engaged by the wheel, yielding means for holding said guard member normally projected inwardly substantially at right angles from the structure, the pivots of said guard members being normally 20 so positioned as to resist upward swinging movement of the members when engaged by the wire during the momentary downward movement of the trolley harp, and means connected to said structure for 25 successively swinging the structure relative to the harp and lowering the harp and wheel, the swinging of the structure being adapted to position the guard members

against the wire to permit said members to slip past the wire. 30

5. In a trolley, the combination with a harp and a trolley wheel, of guard plates pivotally mounted within the harp at each side of the wheel, said plates being connected under the wheel, spring controlled 35 retaining fingers pivotally and slidably connected to each guard plate and normally positioned above the wheel with pivots so located as to resist upward swinging movement of the fingers when pressed downwardly against the wire during the momentary downward jumping of the trolley wheel, and means connected to the guard plates for swinging said plates downwardly and rearwardly, thereby to shift the position of the fingers to permit said fingers to 40 slip past the wire, said last mentioned means being adapted to lower the wheel from the wire. 45

In testimony that I claim the foregoing as 50 my own, I have hereto affixed my signature in the presence of two witnesses.
